UNITED STATES PATENT OFFICE.

H. GORTNER AND J. McCANN, OF NASHPORT, OHIO.

IMPROVEMENT IN CORN-HARVESTERS.

Specification forming part of Letters Patent No. 27,360, dated March 6, 1860.

To all whom it may concern:

Be it known that we, H. GORTNER and J. McCANN, both of Nashport, in the county of Muskingum and State of Ohio, have invented certain new and useful Improvements in Corn-Harvesters; and we do hereby declare that the following is a full, clear, and exact description thereof, reference being had to the accompanying drawings, forming a part of this specification, in which—

Figure 1 represents a vertical longitudinal section taken through our machine from front to rear, as indicated by the red line xx , Fig. 2, showing the position of the hinged framework in red lines for removing the shock of stalks from the machine. Fig. 2 is a plan view of the machine, showing the several parts of the same arranged in their relative positions for cutting and receiving the cornstalks before binding them. Fig. 3 is a transverse section through the cutting apparatus.

Similar letters of reference indicate corresponding parts in the several figures.

The object of this invention is to construct a machine which will, as it is drawn through the field of standing corn, cut the same with great facility, two rows at one time, and by which the cut cornstalks can be readily gathered in shocks and left on the field in a fit condition for binding.

To enable those skilled in the art to fully understand our invention, we will proceed to describe its construction and operation.

In the drawings, A A represent driving-wheels, upon which the front end of the machine is supported.

B is the frame-work of the machine, which is supported in its rear end by caster-wheels a a . At this end of the frame extend up two posts, CC , with a cross-brace, and a roller, D , having its end bearings in either post, and furnished with a winch, E , and pawls and ratchet b .

F are strong cords, having their ends fixed to the roller D and to a hinged frame, G , hinged at its rear end to the frame B , and to the front end of this frame G is hinged a similar frame, G' , its opposite end being free to move with the frame G . This end rests on the longitudinal side bars of the frame B . On one side of the hinged frame G' is hinged another frame, H , which latter receives the cut cane

or stalks as they fall back from the cutters, and for this purpose it is covered with sheet metal or boards and provided with a band, c , which is attached at the middle of its length to a short shaft or roller, d , and by suitable gearing, ee' , the band is wound up on the roller c , after it is secured around the bundle, so as to tighten the band around the bundle, sufficiently to keep the stalks, together until the frame H can be brought over the side of the machine in the position shown in red lines, Fig. 1. Then by loosening the band c the stalks will be discharged on the ground by the side of the machine and out of the way. To bring the bundle of stalks, after they have been bound and secured with the band c , over the side of the machine, as above stated, the frames G and G' are drawn up in a vertical position, as shown in red lines, Fig. 1, by the roller and cords above described, and being held by the ratchet and pawl b , the gate or frame H is then swung round, carrying with it the bundle of stalks. They are then dropped and the parts returned to a horizontal position, (represented by Figs. 1 and 2,) for repeating the operation. In front of this gathering and depositing apparatus are the knives for cutting the stalks, and between these knives is the driver's seat I .

J is a guard-board, and K K' are beveled gearing for operating the knives. The bevel-wheel K is fixed to the shaft of the driving-wheel A , and the wheel K' is attached to a vertical shaft carrying the knives L and a pulley, g . Pulley g gives motion to pulley-wheel g' , which rotates the gathering-arms M . These arms taper from their hub to their extreme ends, and are slightly curved. These rotating arms draw the tops of the stalks over to the knives as the machine proceeds along and throws the cut stalks back on the frame H . They have a slower motion than the knives below, so that the stalks will be drawn up to the cutters as fast only as the cutters perform their work.

N are convex portions, with straight-edged knives f secured to them. Both knives and convex plates N are stationary. Upon these knives and plates N rotate sickle-cutters L , which are bent down so as to conform to the convexity of the fixed knives f . Above these rotary knives L are guards P P' , which prevent

the cutters from carrying the stalks round and round or choking up with the stalks.

Having thus described our invention, what we claim, and desire to secure by Letters Patent, is—

1. The hinged frames G, G', and H, band *c*, roller D, with cords F, all arranged, combined, and operating in the manner and for the purposes herein set forth.

2. The convex knife-rest N, with rotary sickle-blade, and cutters L, as represented and described, and for the purpose specified.

H. GORTNER.
J. McCANN.
